UNITED STATES PATENT OFFICE.

ARTHUR W. ALLBERY, OF WATERFORD, OHIO.

EJECTING-PENHOLDER.

No. 913,933.

Specification of Letters Patent.

Patented March 2, 1909.

Application filed June 3, 1908. Serial No. 436,446.

To all whom it may concern:

Be it known that I, ARTHUR W. ALLBERY, a citizen of the United States, residing at Waterford, in the county of Washington and 5 State of Ohio, have invented certain new and useful Improvements in Ejecting-Penholders, of which the following is a specification.

This invention relates to penholders, and more particularly to that class of holder including means for ejecting a pen, and has for 10 an object to provide a device of this character which may be conveniently applied to pens of ordinary construction, and which will readily serve to effectively discharge a used 15 nib.

A further object of this invention is to provide a device of the above described character which will be simple in construction, composed of but few parts, and which may 20 be manufactured at a relatively low figure.

Other objects and advantages will be apparent from the following description and it will be understood that changes in the specific structure shown and described may be 25 made within the scope of the claims without departing from the spirit of the invention.

In the drawings forming a portion of this specification, and in which like numerals of reference indicate similar parts in the several 30 views, Figure 1 is a side elevational view of the penholder, Fig. 2 is a detail vertical sectional view, Fig. 3 is a top plan view.

Referring now more particularly to the drawings, there is shown a penholder 10 comprising a handle 11 having a reduced stem 12 at one end, as shown. The stem 12 receives an elongated sleeve 13 secured to the stem by means of a rivet or similar fastening device 14. Upon the upper side, the 15 sleeve is provided with a longitudinally disposed slot 15, and upon its under side directly beneath the slot 15 there is a longitudinally extending slot 16. At each side of the slot 15, portions of the sleeve are struck 20 inwardly to form tongues 17 which are curved transversely and which lie in spaced relation to the adjacent portions of the sleeve, as shown in Fig. 4 of the drawings.

It will be noted that the outer ends of the tongues 17 are spaced inwardly of the ends 50 of the slots 15 and 16, the result of which will be subsequently apparent.

An outer sleeve 18 is slidably mounted upon the sleeve 13, and carries a pin 19 extending diametrically therethrough and disposed slidably in the slots 15 and 16 respectively. The sleeve 18 is arranged to lie normally at the inner end of the slots 15 and 16, and its inward movement is limited by the engagement of the pin 19 with the outer end 60 of the stem 12 of the handle. Assuming the sleeve 18 to be at the inward limit of its movement, it is obvious that a pen may be inserted within the sleeve 13 and over the tongues 17 whereby it will be securely held 65 in operative position. When it is desired to eject the pen, the sleeve 18 is moved outwardly and the pin 19 engages the inner end of pen, and moving the pen forwardly until it is free from engagement by the tongues 17; 70 all clamping effect being thus removed, the pen is free to fall from the holder.

What is claimed is:

In a penholder of the class described, the combination with a tubular portion having 75 registering longitudinal slots formed therein stopping short of the forward part of the sleeve, and having opposed tongues stamped inwardly therefrom, the forward edges of said tongues being spaced inwardly of the 80 ends of the slots, for clamping engagement with a pen disposed slidably within the sleeve, of a second sliding sleeve engaged over the first, and a pin member carried thereby and extending diametrically through 85 the first named sleeve and engaged slidably in the slots to retain the second sleeve against displacement and to eject a pen from the first sleeve upon outward movement of the second sleeve. 90

In testimony whereof I affix my signature, in presence of two witnesses.

ARTHUR W. ALLBERY.
